New York, N. Y., a corporation of
Delaware

Application July 5, 1946, Serial No. 681,448

18 Claims. (Cl. 310—70)

1

This invention relates to electrical apparatus and more particularly to current generating and distributing devices of the character adapted for use in ignition systems of internal combustion engines.

One of the objects of the present invention is to provide a simplified magneto generator which is smaller and of lighter weight than prior structures of equal quality and having equal performance characteristics.

Another object of the invention is to provide a structure wherein a magneto generator and current distributing means are combined in a novel and advantageous manner.

A further object is to provide in apparatus of the above character a novel combination of elements for actuating a circuit maker and breaker in timed relation with a magneto and distributor rotor.

Still another object is to provide novel means for connecting and protecting the high tension outlet cables of an ignition distributor or the like.

Another object is to provide a novelly constructed rotor for a magneto generator and means for mounting the same to thereby conserve space and weight.

It is also an object of the invention to provide a novel magnetic rotor for a current generating device which embodies a minimum number of parts and is yet of sturdy construction and efficient in operation.

Still another object is to provide novel means for mounting an ignition coil or the like in a magneto or other device.

The above and further objects and novel features of the invention will more fully appear from the following detailed description when the same is read in connection with the accompanying drawings. It is to be expressly understood, however, that the drawings are for the purpose of illustration only and do not constitute a definition of the limits of the invention, reference for this latter purpose being had primarily to the appended claims.

In the drawings, wherein like reference characters refer to like parts throughout the several views,

Fig. 1 is a horizontal sectional view of one form of apparatus embodying the invention;

Fig. 2 is a side elevation of said apparatus partly in section and with parts broken away, the section being taken substantially on line 2—2 of Fig. 1;

Fig. 3 is an end view looking from the right

2

in Fig. 1 with the coil enclosing portion 11 of the casing and its contents removed; and

Fig. 4 is a diagram of the electrical circuit of said apparatus.

5 A single embodiment of the invention is shown in the drawings, by way of example, in the form of a small half-engine-speed magneto generator equipped with a six pole magnetic rotor and a distributor adapted for use in supplying high 10 tension current to the spark plugs of a six cylinder engine in predetermined sequence. The embodiment illustrated comprises a single two-part housing constituted by a body portion 10 and a cover portion 11. Said housing is adapted 15 to be secured for limited angular adjustment on an engine casing (not shown) through the medium of slotted flanges 12 and suitable studs or bolts (not shown). The parts of the housing are preferably secured together by means of a 20 channel shaped strap 13 but other suitable means may be employed. Mounted within the housing is a magnetic rotor 14 and an ignition coil 15 between which are positioned for suitable cooperation a distributor 16 and a circuit breaker mechanism 17.

The novel and simplified magnetic rotor construction contemplated by the invention comprises a stub shaft 18 rotatably supported by plain or roller bearings 19, 19 in a tubular boss or bearing standard 20 that projects inwardly from the left side or end wall of casing member 10, as viewed in Fig. 1. In addition to supporting said shaft for rotation, said bearings serve to limit the endwise movement or thrust of the rotor shaft. The inner enlarged end of shaft 18 is threaded at 21 and provided with a radially extending bevelled annular flange 22. Mounted on said flange and engaging the bevelled portion thereof is a ring or end plate 23 from which three or other suitable number of equally spaced pole shoes 24 project in the axial direction of the shaft.

45 A second set of pole shoes 25 are similar to pole shoes 24, but extend axially in the opposite direction from and alternate circumferentially with the latter. Pole shoes 25 are shown as being integrally formed with a ring or end plate 26 that is mounted on a cylindrical member or sleeve 27 in engagement with a bevelled flange 28 on the latter. Said supporting cylinder or sleeve is internally threaded for cooperation with the threaded portion 21 of shaft 18 and is thereby supported in spaced relation to boss 20 of casing member 10. Interposed between rings 23 and 50 26 of the pole shoe members and in good mag-

netic contact therewith is a cylindrical magnet which is axially magnetized so that pole shoes 24 and 25 are of opposite magnetic polarity, that is, all of the pole shoes 24 are of one polarity and all of the pole shoes 25 are of the opposite polarity. It will be noted that the pole shoe members and the magnet are clamped together axially between flanges 22 and 28 by threading supporting sleeve 27 onto the threaded portion 21 of shaft 18. Relative rotation of shaft 18, ring 23 and sleeve 27 may be prevented by any suitable means such as a dowel 29, and similar or other suitable means may be provided for fixing sleeve 27 and ring 26 against relative angular movement.

The pole shoes 24 and 25 cooperate in a well known manner with stator pole shoes 30 and 31, respectively, which are cast into or otherwise suitably secured in housing member 10 at opposite sides of rotor 14. The ends of stator shoes 30 and 31 have abutting magnetic contact with the ends of laminated flux conducting members 32 and 33, respectively, which are similarly secured in casing member 11 and tightly embrace the core 34 of ignition coil 15. A magnetic flux path is thus completed through the windings of the coil. With the six pole rotor illustrated and the two pole stator there will be six reversals of flux through core 34 during each revolution of the rotor 14.

The distributor mechanism 16 is novelly associated with the above described parts and comprises a molded block or head 35 of insulating material and a combined circuit breaker cam and distributor rotor 36 consisting for the most part of molded insulating material. Said rotor is secured directly to magnetic rotor 14 by means of a plurality of screws 37. The latter extend through elongated slots 38 (Fig. 3) in rotor member 36 to permit the latter to be angularly adjusted relative to the magnetic rotor for timing purposes. Block or head 35 has a close sliding fit into housing member 11 and fits against a shoulder 39 (Fig. 2) to serve as a closure for the coil and condenser compartment.

A plurality of circularly arranged electrodes 40 and an electrode 41 centrally disposed with respect to the others are molded into or otherwise suitably secured in insulating block 35. Contact member or electrode 41 is permanently connected through a spring 42 with the high potential end of the secondary winding 43 of coil 15, whereas each of the electrodes 40 is connected to a terminal 44 in an insulated socket 45 of a plug and socket connector by means of a cable 46. Said sockets which may be of any suitable construction are mounted in casing member 11 for receiving known types of plug contacts which may in turn be connected with the spark plugs of the engine.

The other end of the central electrode 41 of the distributor has a brushing engagement with a spring finger 47 that is mounted on distributor rotor 36 by means of a screw 48. The latter also secures a radially projecting electrode 49 in electrical engagement with spring 47 and in spark gap relation with the stationary electrodes 40 for successive cooperation therewith during rotation of the rotor. Block 35 and rotor 36 are provided with overlapping or telescoping flanges 50 and 51, respectively, which serve to prevent any flashovers or sparking between the distributor electrodes and the housing or other grounded conducting parts.

The outer peripheral surface of rotor 36 is

provided with a suitable number of lobes 52 (six in the illustrated embodiment) that are best seen in Fig. 3, which are effective to actuate the circuit breaker mechanism 17. The latter may be of any suitable construction, but as illustrated the same comprises a spring-mounted metallic cam follower 53 that is in continuous engagement with the periphery of rotor member 36, a spring mounted insulated contact 54 movable by the cam follower, and a stationary electrically grounded contact 55. The entire circuit breaker mechanism is preferably mounted on a rigid bracket 56 which is mounted for pivotal adjustment about a fixed pivot 51. The six lobes 52 provided on rotor member 36 are thus effective to cause separation and engagement of contacts 54 and 55 six times during each revolution of the magneto rotor—once for each reversal of flux through coil 15.

Parts of the illustrated device including coil 15 and a condenser 58 are held in position and insulated from one another within the compartment in cover member 11 by a suitable insulating compound 59 which is preferably solid and dry when set and yet yielding or resilient. Compounds which have been found suitable for this purpose comprise polymerized cashew-nut-shell or linseed oil with suitable drying agents. The compound completely fills the spaces within and around coil 15 and around the cables, condenser and terminal sockets. By this insulating and securing these parts in position, the cost of making and assembling said parts may be materially reduced without any appreciable risk of failures in operation. The yieldability of the filling material also cushions the parts against shock and vibration.

As best seen in Fig. 2, condenser 58 has one terminal thereof grounded at 60 and the other terminal thereof connected to the insulated contact of circuit breaker 17 through the medium of a resilient connecting means 61. The latter is also connected to the primary winding 62 of the coil by a cable 63 and to the socket 64 of a grounding switch connection by means of cable 65.

In the operation of the above described structure, shaft 18, and hence, magnetic rotor 14 is driven at one-half the speed of the engine crank-shaft through a suitable connection, including gear or splined member 66, to a rotating part of the engine. The rotation of the rotor creates periodic reversals of flux through coil 15 and hence generates an alternating current in the primary winding 62 in a manner which is well known to those skilled in the art. At predetermined intervals in timed relation with the rotor 14, the lobes 52 on rotor member 36 separate at contacts 54, 55 of the circuit breaker thereby breaking the circuit through the primary winding. This in turn results in the induction of a high voltage current in secondary winding 43 which flows through contact members 42 and 41, spring finger 47 and electrode 49, to one of the stationary distributor electrodes 40 which is in turn connected to a spark plug of the engine through cable 46. The apparatus may be rendered inoperative by connecting the insulated contact 54 of the circuit breaker to ground through cable 65 in a suitable grounding switch in a well known manner.

The rotatable elements of the above described device may be driven in either direction. When the same are driven in a counter-clockwise direction, as viewed in Fig. 3, the spring finger 47

and electrode 49 are mounted in the position indicated. When clockwise rotation is desired, these parts may be mounted at the position indicated by numeral 66.

There is thus provided a novelly constructed magneto generator which is of light weight and yet of sturdy construction and which is extremely compact and of small size for its output capacity. Additionally, the construction embodies a distributor encased with the magneto generator in a novel manner whereby space is conserved without increasing the danger of failures resulting from flash-overs or sparking. The novel construction also lends itself to quick and inexpensive assembly and disassembly, with all vital parts readily accessible for inspection and repair.

Although only a single embodiment of the invention is illustrated and described, it is to be expressly understood that the same is not limited thereto. Various changes may be made in the design, size, composition and arrangement of parts without departing from the spirit and scope of the invention as the same will now be understood by those skilled in the art. For a definition of the limits of the invention, reference is had primarily to the appended claims.

What is claimed is:

1. Ignition apparatus comprising a magnetic rotor, a cam member mounted on said rotor for operating a circuit breaker, and a distributor comprising an electrode mounted directly on and within said cam member and a distributor block having an input terminal and a plurality of circularly disposed output terminals operatively associated with said electrode, said block having an axially extending flange surrounding said terminals and extending into a recess in said cam member around said electrode.

2. Ignition apparatus comprising an ignition coil having primary and secondary windings, means including a rotor for energizing said coil, a circuit breaker in circuit with said primary winding, a cam member mounted on said rotor for periodically actuating said circuit breaker, and a distributor comprising a resilient electrode finger mounted directly on and surrounded by said cam member and operatively connected to said secondary winding.

3. In apparatus of the class described a magnetic flux distributing rotor, a coil having primary and secondary windings adapted to be periodically energized upon rotation of said rotor, an electrical current distributing mechanism comprising a block having a plurality of circularly disposed output terminals and a rotatable electrode operatively connected with said secondary winding and being adapted to be periodically moved into spark gap relation with each of said output terminals, said electrode being mounted in a cup-like insulating member secured to said rotor, the outer periphery of said member having a cam surface formed thereon, and a circuit breaker in circuit with said primary winding and operable by said cam surface, said block having an annular flange surrounding said terminals and extending into said insulating member around said electrode.

4. In apparatus of the class described, a two-part metallic casing, a magnetic flux distributing rotor mounted in one part of said casing, a cam member mounted on said rotor for rotation therewith, a circuit breaker operable by said cam member, an ignition coil comprising primary and secondary windings mounted in the other part of said casing,

stator elements mounted in and contacting both of said casing parts for magnetically connecting said rotor and said coil, a distributor block having an input terminal and a plurality of circularly arranged output terminals, said distributor block being mounted in the end of said other part of the casing and closely engaging said stator elements and the surrounding wall of said casing part, and means mounted on said cam element for operatively connecting said input terminal with said output terminals in a predetermined sequence upon rotation of the rotor, said block and cam member having overlapping oppositely extending annular flanges surrounding said output terminals and said last-named connecting means.

5. In apparatus of the class described, a casing comprising a first metallic part and a second metallic part adapted to be secured together to form an enclosure, a magnetic flux distributing rotor and a circuit breaker mounted in said first part, a cam member mounted on said rotor for operating said circuit breaker, a distributor electrode mounted directly on and within said cam member, an ignition coil comprising primary and secondary windings mounted in said second part, means for magnetically connecting said rotor and coil, a distributor block mounted in and completely closing the open end of said second part, terminals in said distributor block operatively associated with said electrode when said casing parts are secured together, said block and cam member having overlapping annular flanges surrounding said terminals and electrode, means for connecting said circuit breaker in circuit with said primary winding, and means for connecting one of said terminals with said secondary winding.

6. In apparatus of the class described, a casing comprising a first part and a second part, a magnetic flux distributing rotor and a plurality of stator pole shoes mounted in said first part in cooperative relation with each other, a plurality of magnetic flux conducting bars mounted in and secured to said second part in end to end relation with said stator pole shoes when said first and second parts are secured together, and an ignition coil mounted in said second part and comprising a core extending between the inner end portions of said flux conducting bars.

7. Ignition apparatus comprising a rotatable cam member for operating a circuit breaker, said member being made of insulating material and having an annular channel in one face thereof adjacent its periphery, a distributor electrode mounted on said member and extending radially from the axis of rotation of said member into said channel, and a distributor block comprising an annular insulating flange extending into said channel, an input terminal operatively connected with said electrode at said axis and a plurality of output terminals surrounded by said flange operatively associated with said electrode.

8. Electrical current distributing apparatus comprising a distributor block having a plurality of circularly arranged output terminals, a portion of each of said terminals extending along the inner wall of a circular flange projecting from the face of said block, a rotor comprising an insulating member having a channel shaped recess in one face thereof for receiving said flange, and an electrode mounted on said member for periodically cooperating with said portion of each of said terminals during rotation of the rotor.

9. A magnetic flux distributing rotor comprising a shaft having a radially extending flange, a cylindrical sleeve having threaded engagement with a portion of said shaft adjacent said flange, a cylindrical magnet surrounding said sleeve, a pair of end plates of magnetic material engaging opposite ends of said magnet, said magnet and plates being clamped between said flange and a radially extending portion of said sleeve, a plurality of pole shoes extending axially in one direction from one of said end plates and circumferentially spaced about the magnet, and a like number of similar pole shoes extending in the opposite direction from the other of said end plates and alternating circumferentially with said first named pole shoes.

10. A magnetic flux distributing rotor comprising a shaft having a flange thereon and an enlarged externally threaded portion adjacent said flange, a cylindrical sleeve surrounding said shaft and having threaded engagement with said threaded portion, a cylindrical magnet surrounding said sleeve, and a pair of end plates engaging opposite ends of said magnet, said magnet and plates being clamped between said flange and radially extending portions of said sleeve, each of said end plates having a plurality of pole shoes formed integrally therewith and extending axially across said magnet externally thereof, the pole shoes of one end plate alternating circumferentially with the pole shoes on the other end plate.

11. A magnetic flux distributing rotor comprising a pair of rotatable plates each having a set of pole shoes extending axially therefrom toward the other plate, a cylindrical magnet interposed between and engaging said plates, a rotatable shaft, and a sleeve extending through said magnet and threadedly engaging said shaft for clamping said plates and magnet between a flange on said shaft and a portion of said sleeve.

12. A magnetic flux distributing rotor comprising a cylindrical magnet, a pair of pole shoe members engaging opposite ends of said magnet, a shaft extending through said magnet, and a sleeve extending through said magnet and threadedly engaging said shaft for securing all of said elements in assembled relation, said magnet and members being clamped between said sleeve and a flange on said shaft.

13. In apparatus of the class described a casing member having an internal hollow boss, a shaft extending through said boss and rotatably supported therein, said shaft having an enlarged externally threaded portion adjacent the inner end thereof and a further enlarged portion constituting a flange at said inner end, a pair of end plates having oppositely directed axially extending pole shoes alternating circumferentially with each other, a cylindrical axially-magnetized magnet surrounding said boss, opposite ends of said magnet being in contact with said end plates, and a sleeve surrounding said boss and extending through said magnet, said sleeve having threaded engagement with said threaded portion of the shaft for clamping said end plates and magnet between said flange and a radially extending portion of said sleeve.

14. In apparatus of the class described an open-ended casing member, a pair of flux conducting bars mounted in and secured to said member, a flux conducting core frictionally held between end portions of said bars, an ignition coil comprising primary and secondary windings wound on said core, a condenser in and detached

from said casing member, a plurality of terminal sockets extending into said member, means for closing the open end of said member, conducting elements in said last-named means electrically connected to said coil and condenser, and solid insulating means completely filling the closed spaced in said casing member around said coil, condenser and terminal sockets.

15. In apparatus of the class described, a casing comprising a first part and a second part, a magnetic flux distributing rotor mounted in said first part, an ignition coil having a core mounted in said second part, flux conducting means mounted in and secured to said first part and operatively associated with said rotor, flux conducting means mounted in and secured to said second part and operatively associated with said core, said means being in abutting relation with each other, whereby periodic reversals of magnetic flux through said coil are effected upon rotation of said rotor, and an ignition distributor interposed between said coil and rotor.

16. In apparatus of the class described, a casing comprising a first part and a second part, a magnetic flux distributing rotor mounted in said first part, an ignition coil having a core mounted in said second part, flux conducting means mounted in and secured to said first part and operatively associated with said rotor, flux conducting means mounted in and secured to said second part and operatively associated with said core, said first named flux conducting means being in abutting relation with said second named flux conducting means, whereby periodic reversals of magnetic flux through said coil are effected upon rotation of said rotor, and an ignition distributor interposed between said coil and rotor, said distributor comprising a rotatable electrode carried by said rotor and a distributor block mounted in and closing the opened end of said second part.

17. In a magneto: the combination of a metal housing; a rotor in said housing; a stator having pole elements diametrically opposite said rotor and extending longitudinally of the rotor and having a core member bridging the outer ends of said pole elements; an induction coil on said core member; an interior metal standard on said housing extending from one side of said housing into the space between said pole elements and terminating short of the other side of the housing; a journal bearing in said standard; a shaft of said rotor extending through said bearing; a breaker cam on the end portion of said shaft beyond said bearing; and a circuit breaker mounted on said housing in the space between said stator pole elements and including a movable breaker arm coacting with said cam.

18. In a magneto including a metal housing: the combination of an integral interior standard on said housing projecting from one wall thereof partially to the opposite wall thereof; a rotor having a shaft journaled in said standard and extending therebeyond; a stator having pole elements at opposite sides of said rotor and extending longitudinally of the rotor past said standard, and a core element bridging the outer ends of said pole elements; an induction coil on said core element; a breaker cam on an end of said shaft in the space between said pole elements; and a circuit breaker comprising a breaker arm at the outer side of said standard

having a free end portion actuatable by said breaker cam.
